UNITED STATES PATENT OFFICE.

ABRAHAM NOVICK, OF NEW YORK, N. Y., ASSIGNOR, BY MESNE ASSIGNMENTS, TO UNITED STATES ENVELOPE COMPANY, OF SPRINGFIELD, MASSACHUSETTS, A CORPORATION OF MAINE.

CUTTING MECHANISM FOR ENVELOP-BLANKS.

1,310,922.

Specification of Letters Patent. Patented July 22, 1919.

Application filed November 28, 1916. Serial No. 133,976.

To all whom it may concern:

Be it known that I, ABRAHAM NOVICK, a citizen of the United States, residing at New York, in the county of Kings and State of New York, have invented a new and useful Improvement in Cutting Mechanism for Envelop-Blanks, of which the following, together with the accompanying drawings, is a specification.

16 My present invention relates to a cutting mechanism for shaping and severing envelop blanks from a continuous web of paper, and it is adapted to form a part of an envelop machine of the type known as 15 rotary.

The objects of my invention are to simplify the construction of rotary cutting mechanisms for forming envelop blanks from a continuous web; to enable the incisions in the continuous web to be more accurately formed, and to facilitate the renewal of the cutting blades. These objects, among others, I accomplish by the construction and arrangement of parts as hereinafter 25 described, the features of novelty being pointed out in the appended claims.

Referring to the accompanying drawings,

Figure 1 is a plan view of so much of a 30 rotary envelop machine as is necessary to illustrate the character of my present invention, the upper or bed rolls coöperating with the cutting rolls having been removed.

Fig. 2 is an enlarged view of the first 35 cutting roll, containing the cutter for cutting one side of the lozenge shaped opening in the center of the web.

Fig. 3 is a transverse sectional view on the plane of the broken line 3—3, Fig. 2.

Fig. 4 is an enlarged view of the second 40 cutting roll showing the central cutter in place for completing the lozenge shaped opening in the center of the web, and also showing the recesses for receiving the cutters for forming notches in the edges of 45 the web.

Fig. 5 is an enlarged view of the second cutting roll, showing the cutters in position for cutting two of the four notches formed in the edges of the web, and also showing 50 a recess for receiving the central cutter.

Fig. 6 is a sectional view on the plane of the broken line 6—6, Fig. 5 of one of the

cutters for forming notches in the edges of the web.

Fig. 7 is an enlarged view of the second 55 cutter roll, showing the cutters in position for forming the two remaining notches of the four notches formed in the edges of the web.

Fig. 8 is an enlarged view of the roll carrying cutters for severing the web to form 60 individual envelop blanks.

Fig. 9 is a transverse sectional view on the plane of the broken line 9—9, Fig. 8.

Fig. 10 is a sectional view of the entire 65 cutting mechanism on the plane of the broken line 10—10, Fig. 1.

Fig. 11 is a diagrammatic view showing a portion of the continuous web and representing the incisions made therein by full 70 lines, and showing the lines of fold of the envelop blank by broken lines.

Fig. 12 is a detached view of one of the cutting blades for cutting one side of the central opening in the web, and

Fig. 13 is a detached view of one of the edge cutters for forming a notch in the edge of the web.

Similar reference characters refer to similar parts in the different figures.

Referring to Fig. 11 of the drawings, 1 denotes a portion of the continuous web from which the envelop blanks are formed by means of the cutting mechanism, said figure showing the adjacent ends of two envelop blanks, each comprising a seal flap 2, back flap 3 and end flaps 4 and 5. The blanks when severed from the continuous web are finally folded on the broken lines 6. In shaping the blanks to form the flaps 85 90 of the envelop, I make four notches in the edges of the web, namely notches 7 and 8 on one edge of the web, and notches 9 and 10 on the opposite edge of the web. I also form an opening 11 in the center of the web between adjacent blanks, said opening being substantially lozenge in shape and having two acute angles 12 and 13 and two obtuse angles 14 and 15. When the above named incisions have been made in the web, 10 the web is severed on lines 16 and 17, the line 16 joining the acute angle 12 and the apex of the notch 7, and the line 17 uniting the angle 13 and the apex of the notch 9.

The cutting of the web is accomplished by passing the web between rolls arranged in pairs, one roll of each pair, preferably the lowermost, carrying a cutting knife coöperating with the uppermost, forming a bed roll to sever the web. The arrangement of the cutting and bed rolls is illustrated in Fig. 10, in which the rolls 18, 19 and 20 form the cutting rolls, and the rolls 21, 22 and 23 10 constitute the bed rolls coöperating therewith, said bed rolls having been removed from Fig. 1 in order to disclose the position of the cutting knives on the cutting rolls.

The opening 11 in the center of the web 15 is formed by two separate operations, the first cutting the lines 24 and 25 inclosing the obtuse angle 15, and the second operation cutting the lines 26 and 27 inclosing the obtuse angle 14. The cutters performing 20 these two operations are mounted upon separate cutting rolls, in the present instance upon rolls 18 and 19 which coöperate with the bed rolls 21 and 22 respectively.

I am aware that it has been proposed to 25 cut a similar lozenge shaped opening in the center of the web by means of a cutter which forms the opening at a single operation, the cutter being made in a single piece and having cutting edges for cutting the 30 four sides of the figure. Cutters of this type are difficult to construct and difficult to sharpen, as the acute angles 12 and 13 are extremely pointed. The sides 24 and 26 are slightly curved and are tangential to 35 the line 16, upon which the web is severed upon one side of the opening 11. Likewise, the sides 25 and 27 are slightly curved and are tangential to the line 17, upon which the web is severed upon the other side of 40 the opening 11. The lines 24 and 25 are formed by a single cutter 28 carried upon the roll 18, shown in Fig. 1, and represented on a large scale in Fig. 2. The cutter 28 is 45 formed of a single piece of sheet steel, as shown in sectional view in Fig. 3, which is swaged by suitable dies into proper form to correspond with the desired curvature of the lines 24 and 25, Fig. 11, and is beveled upon one edge to form a cutting edge 29. 50 The cutter is cheaply constructed and easily beveled throughout its length. As it is of uniform thickness, it is readily tempered to provide an efficient cutting edge.

The cutter 28 when completed is attached 55 by screws 30 to the side of a block 31, having its outer curved surface concentric with the axis of the roll upon which it is mounted. The surface of the block 31 to which the cutter 28 is attached is suitably shaped 60 to bring all parts of the cutting blade in a radial plane, so that any pressure upon its outer cutting edge 29 will be directed toward the center of the roll 18. The segmental block 31 is attached by screws 32 to a plate 65 33 upon which the inner edge of the cut-

ting blade 28 rests. The plate 33 rests upon spiral springs 34 held in recesses 35 formed in a base plate 36, which rests upon a diametrically slabbed surface 37 of the roll 18. The base plate 36 is attached to the roll by 70 screws 38 having polygonal heads 39 to receive a wrench. The screws 38 pass through enlarged holes in the base plate 36 and plate 33 to permit the position of the cutter blade 28 to be slightly changed, which is accomplished by loosening the screws 38, which bear by their shoulders 40 on the base plate, and by moving the latter in any direction desired to secure the proper position of the cutting blade 28.

The outward movement of the plate 33 is limited by the heads 41 of screws 42, which are held in the base plate 36. The cylindrical surfaces 43, 43 of the roll 18 upon each side of the cutter 28 coöperate with the surface of the bed roll 21 to feed the continuous web forward, and the cutter blade 28 is radially adjusted by means of the screws 42 to bring its cutting edge into contact with the cylindrical surface of the bed roll 21, 90 causing it to be slightly forced inwardly against the pressure of the springs 34 and effecting an incision in the web corresponding to the outline of the cutting edge 29.

From the rolls 18 and 21 the web passes 95 between the rolls 19 and 22, the roll 19 forming the second cutting roll and the roll 22 its coöperating bed roll. The cutting roll 19 is provided at its center with a cutting blade 44 constructed like the cutting blade 100 28 already described, from a single piece of sheet steel swaged into proper shape to cut the web on the lines 26, 27, Fig. 11, and thereby complete the formation of the lozenge shaped opening 11 in the center of the 105 web. The mounting of the cutting blade 44 upon the roll 19 is like that already described with reference to the cutting blade 28. The cutting blade 44 is attached by screws 45 to the side of a segmental block 110 46, which is mounted upon a plate 47 resting on springs, indicated by the broken lines 34, held in recesses formed in a base plate, not shown, but corresponding to the base plate 36, Fig. 3, said base plate being held 115 down upon the slabbed surface of the roll 19 by means of screws having polygonal heads 49. The roll 19, in addition to carrying the central cutting blade 44, is cut away or slabbed upon opposite sides to form recesses 120 for cutters suitably shaped and positioned to form the notches 7, 8, 9 and 10 in the opposite edges of the web. These edge cutters consist of the blades 50 and 51, Fig. 5, and of blades 52 and 53, Fig. 7. The cutting blades 50, 51, 52 and 53 are formed from single pieces of sheet steel swaged into proper form, and beveled on one edge to form a cutting edge, and are attached by screws to segmental blocks 54, 55, 56 and 57. 130

As the method of mounting each of these cutters is the same, a description of cutter 51 will suffice.

The cutter 51, Fig. 5, is shown in sectional view in Fig. 6. The cutter 1 is attached by screws 58 to the segmental block 55. The segmental block 55 is attached by screws 59 to a plate 60 resting upon springs 61. The plate 60 is held from outward movement by the heads of screws 62 which pass through blank holes in the plate 60 and are screwed into the roll 19. From the rolls 19 and 22 the web, having the notches 7, 8 and 9, Fig. 11, cut in its edges and having the incisions made on the lines 24, 25, 26 and 27, Fig. 11, passes to rolls 20 and 23 containing the severing blades 63 and 64, Fig. 8, which sever the web on the lines 16 and 17, Fig. 11, said lines connecting the acute angles 12 and 13 with the apices of the notches 7 and 9. The mounting of the severing blade 63 is illustrated in sectional view in Fig. 9, and as the severing blade 64 is similarly mounted, a description of the mounting of blade 63 will suffice.

The roll 20, upon which the severing blades are mounted, is slabbed diametrically to receive a blade holding block 65 resting upon the slabbed surface of the roll 20 to which it is attached by screws 66, said screws passing through enlarged holes in the flanged base of the block 65 to permit the latter to be adjusted slightly upon the roll in order to vary the position of the severing blades. The block 65 is longitudinally recessed to receive the blade 63, which rests upon a series of spiral springs 67 placed under the edge of the severing blade 63, one of which is shown in Fig. 9. The blade 63 is provided with a shoulder 68 which is overlapped by the heads of screws 69 held in the block 65, one of which is shown in Fig. 9.

Between the pair of rolls 19 and 22 and the pair of rolls 20 and 32 I place a pair of rolls 70 and 71 with their peripheries running in contact with the web, thereby serving as feeding rolls, like the rolls 18 and 21, to forward the web past the cutting rolls. I also incorporate with the rolls 70 and 71 chip removing devices for removing the severed pieces of paper from the web, but as these chip removing devices form no part of my present invention, it is unnecessary to describe them. The rolls 19 and 20 are provided at their ends with slight flanges 72, Figs. 4 and 8, which run in contact with their coöoperating bed rolls 22 and 23, the body portion of these rolls being slightly recessed to clear the web except as their projecting cutting blades contact with the web. To insure the engagement of the cutting blades carried by the rolls 18 and 20 with the surface of the web, the cutting edges of the blades are

caused to project slightly beyond the periphery of the flanges 72, so they will impinge against the peripheries of the bed rolls 22 and 23 and be pressed down upon their respective supporting springs. The web of paper is thereby held taut between the bite of the respective pairs of feeding rolls, while the cutting rolls run free of the web except as the latter is engaged by the cutting blades. No pressure is, therefore, imparted to the web during the operation of cutting, except upon lines coincident with the sharpened edges of the cutting blades.

A detached view of one of the central cutters, 28, is shown in Fig. 12, and in Fig. 13 I have shown a detached view of one of the edge cutters, 51. Figs. 12 and 13, will, therefore, illustrate the method of forming each of the cutters from a single piece of sheet steel, the only difference between the cutters being in their size and shape.

By the above described method of forming the cutting blades and mounting the same upon the cutting rolls, I greatly reduce the cost of constructing the blades, which are so readily and cheaply made that new blades may be substituted for old ones at slight cost. The blades are also easily sharpened, either in their positions on the rolls or each blade may be removed by withdrawing two screws. By forming the central lozenge shaped opening 11 by two operations, cutting only one side at a time, I am enabled to make the incisions at the two ends of the blade 44 overlap the incision made by the ends of the blade 28, thereby enabling the ends of the opening 11 to be brought to sharp points. The adjustability of the central blades 28 and 44 and the severing blades 63 and 64 makes it possible to sever the blank on lines 16 and 17, Fig. 11, so as to accurately join the notches 7 and 9 with the points of the opening 11. The amount of pressure exerted to sufficiently sever the web is measured by the pressure of the springs supporting the cutting blades, thereby enabling the operator to provide the requisite pressure by a choice of springs.

I claim:

1. In a mechanism of the class described, a pair of rolls for forwarding a continuous web, one of the rolls in said pair carrying a knife coöperating with the other roll of the pair for forming part of an opening in the center of the web, a second pair of rolls with one of the rolls of the pair recessed to clear the web, knives carried by said recessed roll and coöperating with the other roll of said second pair of rolls to complete the center opening in the web and to form notches in the edge of the web, and a third pair of rolls contacting with the web to forward the same, all of said pairs of rolls operating upon the web in the order named.

2. In a mechanism of the class described, a pair of coöperating rolls for forwarding the web, a knife carried by one of said rolls for severing the web to form part of an opening in the center of the web, a second pair of coöperating rolls, a knife carried by one of the rolls of said second pair for completing the opening in the center of the web, and also a pair of knives for notching the edges of the web. 10
3. In a mechanism of the class described, a pair of coöperating web forwardly rolls, one of the rolls of said pair carrying a yielding cutter knife for cutting one side of an opening in the center of the web, a second pair of coöperating rolls, with one roll of said second pair carrying yielding knives for completing the opening in the center of the web and forming notches in the opposite edges of the web, a third pair of coöperating rolls for forwarding the web, a fourth pair of rolls carrying knives for severing the web on each side of its center opening, and a fifth pair of coöperating rolls for continuing the forward movement of the web, said pairs of rolls being arranged to operate upon the web in the order named. 15
4. In a mechanism of the class described, means for forwarding a continuous web, a pair of coöperating rolls for forming an opening in the edge of the web, one of said pair of rolls having a slabbed surface, a yielding plate supported on said surface, a segmental block mounted on said plate, and a cutting knife attached to the edge of said block. 30
5. In a mechanism of the class described, means for forwarding a continuous web, means for forming an opening in the edge of the web, comprising a coöperating pair of rolls, one of said rolls having a slabbed surface provided with recesses, springs held in said recesses, a yielding plate supported on said springs, a segmental block mounted on a portion of said plate, and a cutting knife attached to the edge of the segmental block. 40
6. In a mechanism of the class described, means for forwarding a continuous web, means for cutting an opening in the center of the web, comprising a pair of coöperating rolls, one of said rolls having a slabbed surface, an adjustable base plate held on said surface, a yielding plate outside said base plate, a segmental block attached to said
- yielding plate and having an exposed edge in a radial plane and a cutting knife attached to said exposed edge. 5
7. In a mechanism of the class described, the combination with a series of cutting rolls for shaping the blanks from a continuous web and for severing the web to form individual blanks, of a series of non-cutting conveying rolls for forwarding the blank alternating with the cutting rolls. 60
8. In an envelop blank cutting mechanism, a pair of coöperating rolls, one of the rolls of said pair having a slabbed surface for supporting a cutting knife, a plate adjustably attached to said surface, a radially yieldable plate spaced from said adjustable plate, springs supporting said yieldable plate, a block attached to said yieldable plate having one of its edges in a substantially radial plane, and a sharpened blade detachably held on the radial edge of said block with its sharpened edge projecting beyond the periphery of the roll. 65
9. In an envelop blank cutting mechanism, means for forwarding a continuous web, cutting means for shaping an envelop blank and a pair of web severing rolls for separating the shaped blanks from a web, one of the rolls of said pair having a diametrically slabbed surface for supporting cutting knives, a block adjustably held on said slabbed surface provided with a longitudinal recess, a cutting knife held in said recess, a yieldable support for said knife, and means for limiting the outward movement of said knife. 70
10. In a mechanism of the class described, means for forwarding a continuous web, means for forming an opening in the center of the web, and means for severing the web between said opening and the edges of the web, comprising a pair of coöperating rolls, one of said rolls having diametrically slabbed surfaces, a pair of blocks adjustably held on said slabbed surfaces and having longitudinal grooves, a pair of knives held in said grooves, springs for forcing said knives radially outward beyond the peripheries of the roll, and means for limiting the outward movement of the knives. 75

Dated this 15th day of November, 1916.
